UNITED STATES PATENT OFFICE.

MICHAEL SETTER, OF CHICAGO, ILLINOIS, ASSIGNOR TO AMERICAN ELECTRIC TELEPHONE COMPANY, OF CHICAGO, ILLINOIS, A CORPORATION OF NEW JERSEY.

SELECTIVE SIGNALING APPARATUS.

1,185,843.

Specification of Letters Patent.

Patented June 6, 1916.

Application filed June 6, 1906. Serial No. 320,442.

To all whom it may concern:

Be it known that I, MICHAEL SETTER, a citizen of the United States of America, and resident of Chicago, Cook county, Illinois, 5 have invented a certain new and useful Improvement in Selective Signaling Apparatus, of which the following is a specification.

My invention relates to selective signaling systems in general, but more particularly to 10 selective signaling systems for telephone party lines, and especially to party line systems in which the operator is provided with a selective ringing key having a plurality of keys or push-buttons, each representing a 15 different substation on the party line.

Generally stated, the object of my invention is the provision of an improved and highly efficient selective ringing or signaling apparatus.

20 Special objects are the provision of an improved selective ringing key having push-buttons or keys adapted by improved mechanism, to serve as indicating devices for enabling the operator at once to locate or 25 determine which of the different substations was called; the provision of an improved construction and arrangement whereby the push-buttons or ringing keys allotted to the different substations are adapted to remain 30 in a partially depressed position, and to be depressed from such intermediate position for the purpose of repeating the ringing of the called subscriber's bell; the provision of a construction and arrangement whereby the 35 push-buttons of the selective ringing key may each be restored to normal position by the actuation of the operator's ordinary key lever for use in ringing subscribers who are not located on a party line; the provision of 40 an arrangement whereby the actuation of a combined ringing and listening key lever to ringing position permits the push-button to be restored; and the provision of certain details and combinations and features of improvement tending to increase the general 45 efficiency and serviceability of apparatus of this particular character.

To the foregoing and other useful ends, my invention consists in the matters hereinafter set forth and claimed.

In the accompanying drawings, Figure 1 is a side elevation of an operator's selective ringing key embodying the principles of my invention, showing an ordinary operator's 55 listening and ringing key in conjunction

therewith; Fig. 2 is an end elevation of the same; Fig. 3 shows the other end of the said selective ringing key arrangement; Fig. 4 is a view of the other side of the said operator's ringing key arrangement, showing a portion of the same in vertical section; Fig. 5 is a top view of the structure shown in Fig. 4; Fig. 6 is a vertical section on line 6—6 in Fig. 1; Fig. 7 is a detailed vertical section on line 7—7 in Fig. 1; Fig. 8 is a diagram of a party line telephone system, illustrating the application of my improved selective ringing apparatus to use in selectively ringing the different subscribers on the party line.

As thus illustrated, and referring more particularly to Figs. 1 to 7, inclusive, it will be seen that my improved operator's ringing key arrangement comprises a top plate A, provided with sockets or openings for a plurality of push-buttons 1, 2, 3 and 4. Each push-button is held in its normal or raised position by a spring B. The lower end of each push-button is preferably tapered, as shown more clearly in Fig. 4. Each push-button has mounted below it a group of switch springs adapted to control the line and ringing circuits and adapted to be operated by the said push-buttons. For example, the push-buttons 1, 2, 3 and 4 are provided respectively with groups of switch springs C, D, E and F. As will hereinafter more fully appear, these switch springs are connected with the operator's cord circuit and are so arranged that when any button is pressed it operates its allotted springs and thereby opens the line circuit and connects the ringing generator with the line of the called subscriber, and for this purpose the said switch springs may be of any suitable known or 90 approved character. The said springs are mounted in a strip of insulation G, secured along the lower edge of the flat side plate H, which latter is secured in a suitable manner to the top plate A. Upon the outside of 100 the plate H are mounted a plurality of locking dogs for catching and holding the push-buttons in partially depressed positions. For example, the push-buttons 1, 2, 3 and 4 are provided respectively with locking dogs 5, 6, 7 and 8, said dogs having their lower ends pivoted to the said side plate H. The said dogs are all connected together by means of a connecting bar 9, which latter has an upwardly projecting arm 10 provided 110

with a slot 11. The said bar also has a slot 12, through which extends a screw 13, by which the said arm 10 is held and guided, said screw extending into the side plate H. 5 A spring 14 connects the bar 9 with the side plate H and is so tensioned that it keeps the dogs in their normal positions. At their lower ends the said push-buttons are provided respectively with pins 15, 16, 10 17 and 18, adapted to slide in the vertical slots h formed in the plate H. Said push-buttons are also provided with pins 19, which slide up and down in said slots and normally engage the under side of the top 15 plate A. With this arrangement each push-button is adapted to be depressed for the purpose of operating its allotted switch springs and to then rise until it is caught by its allotted dog. For example, the push-button 1 can be depressed until its springs are suitably operated, and can then rise until its pin 15 is caught and held by the dog 5. In such partially depressed position the said push-button serves as an indicator for enabling the operator to at once determine which subscriber she was calling. Should the subscriber not answer, she can then depress the push-button from its intermediate position for the purpose of again closing 20 the ringing generator in connection with the line of the called subscriber. In other words, instead of asking the calling subscriber what number it was that he called, the operator simply looks at her selective 25 switch key and sees immediately which subscriber is wanted. In this way the operator can receive the order for connection and ring the called subscriber, and can then again ring the called subscriber several 30 times, without the necessity of remembering the called number and without the necessity of asking the calling subscriber to repeat such number.

Each locking dog is beveled at its upper 45 surface. In this way a depression of any push-button necessarily restores to normal position any other push-button which may have been left in a partially depressed position. In other words, with this arrangement 50 no two push-buttons are liable to be found down at the same time. The arrangement as a whole also comprises an ordinary operator's ringing and listening key lever I. This lever is, as will be seen, pivoted at i and 55 provided with a pin i', adapted to engage the slot 11. The said key lever is also provided with rollers i², adapted to engage and operate the listening springs i³ and the ringing springs i⁴. With this arrangement the 60 push-buttons may be operated without moving the lever I, as the pin i and the slot 11 constitute a lost motion connection, so to speak, between the said lever and the arm 10. It will be observed, however, that when 65 the key lever I is thrown to a ringing posi-

tion, the movement thereof is then sufficient to pull all of the dogs out of engagement with any push-buttons which may happen to be down. Preferably, the construction is such that when the said key lever I is 70 thrown to listening position it will remain there and continue to maintain the connection of the operator's head telephone with the line until the operator gets the order for connection. With the provision of the said lost motion connection the said key lever I can be thrown to listening position without producing any movement of the bar 9. With this arrangement the push-buttons can be operated and each time one is operated to 80 ring a particular party on the line it can restore the button which was last operated. Then suppose that the operator finds it necessary to use the key I for ringing a subscriber on an ordinary line. In such case 85 the movement of the said key lever, namely the rocking of the said lever into ringing position, effects a restoration of the push-button which was last used by the operator. Thus any push-button can be restored by 90 any other push-button and can also be restored by the operation of the operator's combined listening and ringing key. In this way the key lever I serves as a restoring 95 key for the four push-buttons of the selective ringing switch.

Referring to Fig. 8, the operation is as follows: The calling subscriber J has a suitable line connection with the central station, said line terminating in the spring-jack j. The calling subscriber operates the line signal j' and thereby obtains the attention of the operator. The latter then inserts her answering plug K in the answering jack of the calling subscriber's line and receives 100 the order for connection, and in order to do so she must rock the key lever I to listening position so as to connect her telephone set L with the calling subscriber's line. It will be understood that during such operation the 105 switch plug l connected with the operator's head telephone is inserted in the socket l'. Upon learning the number of the called subscriber the operator then inserts the calling 110 plug M in the jack connected with the called subscriber's line. Suppose the calling subscriber desires connection with a subscriber on a single line, as, for example, the line N leading 115 to a substation like the substation J. In such case the operator simply plugs in and then swings the key lever I to ringing position, thus bridging the low frequency current generator O across the called subscriber's line. This will ring the called subscriber's bell in the ordinary and well understood 120 manner. Suppose, however, that the calling subscriber desires connection with a party line subscriber. For this purpose, assume 125 that the calling subscriber desires connection with the party line subscriber P. In such 130

case the operator first inserts the calling plug M in the jack Q connected with the party line q. She then operates the push-button 1 and thereby connects the high frequency current generator R with the said party line,—that is to say, with the sleeve side of the said party line, it being observed that the ringer or bell p allotted to the subscriber's substation P is connected with the 10 so-called sleeve side of the line. When this is done, current passes from the said generator R through the conductor 20 to the contact point 21, thence through the spring C to the other springs in series, and through the conductor 22 to the sleeve contact 23 of the said calling plug, thence over the sleeve side of the line to the bell p and through the condenser p' to ground 24, thence through ground to the ground connection 20 25 which is common to the high and low frequency generators. It will be understood at this juncture that the said generators may be inductively connected with their leads, as indicated in Fig. 8. This will ring the 25 bell at the called subscriber's station. Should the subscriber at substation S be called, the operator will then establish a connection in the same manner, but she will then press the key 3 and thereby connect the 30 low frequency generator O with the sleeve side of the party line. The high frequency generator can be connected with the tip side of the party line by pressing the push-button 2 and the low frequency generator can 35 also be connected with the tip side of the said party line by pressing the push-button 4.

As previously explained, each time that the operator listens in and receives the order for connection from the calling subscriber, 40 she necessarily, by afterward shifting the key to ringing position, then restores the push-button last employed in calling a party line subscriber. Suppose that after properly establishing connection between the calling 45 and called lines, and after ringing the bell at substation P, the operator gives her attention to other things, and then in a few moments the calling subscriber informs her that the called subscriber has not answered.

50 With my improved arrangement it will not be necessary for the operator to then inquire as to the number of the called subscriber, for by a glance at her selective

ringing switch she can know in a moment what subscriber it was that she was calling. 55 The push-button allotted to the called subscriber is still partially depressed, so that she simply selects this push-button and presses it again, thereby again ringing the bell at the called substation. The high frequency bell at the substation T is rung by 60 pressing the push-button 2, while the low frequency bell at the substation U is rung by pressing the push-button 4. It will be understood, of course, that the selectively 65 operated bells or ringers at the substations can be of any suitable known or approved character. I do not, however, limit myself to any particular form of selective bells or ringers. Neither do I limit myself to any 70 particular form or character of telephone system.

What I claim as my invention is:

1. In a telephonic switching device, an operator's key, a plurality of actuating buttons, switching mechanism associated with said operator's key and with said actuating buttons, a plurality of dogs associated with said buttons adapted to hold the same in depressed position, a bar associated with said 75 dogs and having a loose connection with said operator's key whereby operation of said key operates said dogs through the medium of said bar to release a depressed button.
2. In a telephonic switching device, an 80 operator's key, a plurality of actuating buttons, switch mechanism associated with said operator's key and the said actuating buttons, a dog associated with each of said buttons adapted to lock a button in position 85 upon depression thereof, means for operating said dogs to release a depressed button, said means including a bar having an upwardly extending arm and a loose connection between said arm and said operator's 90 key whereby a complete operation of said key would operate said bar but a limited operation of the said key is permitted without operating said bar.

Signed by me at Chicago, Ills., this 24th 100 day of May 1906.

MICHAEL SETTER.
